UNITED STATES PATENT OFFICE

141,674

DESIGN FOR AN AIR-MAIL ENVELOPE

Vera Bock, New York, N. Y., assignor to United States Envelope Company, Springfield, Mass., a corporation of Maine

Application November 27, 1944, Serial No. 116,574

Term of patent 14 years

(Cl. D59—8)

To all whom it may concern:

Be it known that I, Vera Bock, a citizen of the United States, residing at New York, in the county of New York and State of New York, have invented a new, original, and ornamental Design for Air-mail Envelopes, of which the following is a specification, reference being had to the accompanying drawing, forming part thereof, in which:

Fig. 1 is a front view of an air-mail envelope showing my new design.

Fig. 2 is a rear view of said envelope, showing my new design.

The drawing is lined for color.

I claim:

The ornamental design for an air-mail envelope, as shown and described.

VERA BOCK.
